UNITED STATES PATENT OFFICE.

EDWARD ALFRED GRAHAM, DECEASED, LATE OF BROCKLEY, LONDON, ENGLAND, BY MARIA GRAHAM, EXECUTRIX, OF BECKENHAM, ENGLAND, AND ALFRED GRAHAM, EXECUTOR, OF FOREST HILL, LONDON, ENGLAND, ASSIGNEES TO GRAHAM AMPLION LIMITED, OF LONDON, ENGLAND.

ACOUSTIC AMPLIFIER AND RADIATOR.

Application filed December 24, 1926, Serial No. 156,967, and in Great Britain February 20, 1926.

In the specification of an application Serial No. 97,130, filed by Edward Alfred Graham, of whom we are executors, for Letters Patent, there is described an invention having for its object to provide an improved acoustic amplifier and radiator which shall be suitable for use with apparatus in which sound waves are produced or originated by the vibration of a diaphragm, 5 as in the case of an electro-magnetic telephonic receiver, or the sound box of a gramophone, which shall be compact in form, suitable for embodying in a cabinet or casing, and highly efficient in use, quality of tone 10 being maintained, together with maximum volume.

The invention as described in the said prior specification, is characterized in that the sound amplifying and radiating means 20 adapted to co-act with a sound directing conduit, comprises multiple concave reflecting surfaces one of which is of comparatively large curvature and blends into another which is of comparatively small curvature, 25 the arrangement being such that sound waves projected on to such an amplifier will be radiated therefrom and diffused through the outlet orifice of such acoustic amplifier and radiator.

Now the present invention is an improvement in or modification of the invention claimed in the said earlier specification, the improvement or modification consisting in this that although multiple reflecting surfaces are employed, they comprise a concave 35 surface and one or more flat surfaces, the single flat surface, or one at least of such flat surfaces when several are used, being inclined to the outlet orifice of the acoustic 40 amplifier and radiator.

Thus, the acoustic amplifier and radiator comprises a reflecting element having a concave reflecting surface and one or more flat secondary reflecting surfaces such as referred 45 to, and a sound wave developing conduit, the concave reflecting surface and sound conduit being so arranged in relation to each other and to the flat reflecting surface or surfaces that sound impinging on the concave surface 50 will be reflected therefrom and thence be radiated and diffused through the outlet orifice of the acoustic amplifier and

radiator by the flat reflecting surface or surfaces.

Such a combination of reflecting surfaces 55 can be constructed in numerous ways, each being characterized by its compactness of form and adaptability to be housed or embodied, if so desired, in a cabinet or other enclosure.

In the accompanying illustrative drawings, Fig. 1 shows in front elevation, a cabinet embodying one construction of acoustic amplifier and radiator according to the present invention. Fig. 2 shows the acoustic amplifier and radiator in front elevation, the upper portion of the cabinet being raised for the purpose. Fig. 3 is a horizontal section on the line III—III of Fig. 1. Figs. 4, 5, 6 and 7 are horizontal sections showing modified constructions. Figs. 8 and 9 are perspective views showing further modifications. Fig. 10 shows in front elevation a still further modification.

Figs. 1, 2 and 3 show one example of an 75 acoustic amplifier and radiator according to the invention, particularly applicable as a sound amplifying and radiating chamber for a loud speaking telephone. It consists of a trough or scoop-like structure comprising 80 a vertically arranged reflecting element 1 having a concave reflecting surface (hereinafter called the concave reflector) a vertically arranged flat reflecting surface 4 (hereinafter called the flat reflector) constituted 85 by a wall inclined to the axis of the concave reflector 2 and to the outlet orifice A of the structure, a vertical rear wall 5 connecting the rear ends of the concave and flat reflectors 1 and 4 and arranged parallel to the outlet orifice of the structure and which may or 90 may not act as a reflector, and top and bottom walls 6 and 7 which extend over and under the concave and flat reflectors 1 and 4 and rear wall 5. The reflector 1 which, 95 in horizontal section is of parabolic shape, is adapted to coact with a sound wave developing conduit 2 that is of gradually increasing cross sectional area and carries at its constricted end, a telephonic receiving 100 unit 3. The sound conduit 2, which in this example is straight and arranged with its axis co-axial with the principal axis x—x of the concave reflector 1, is carried by the flat

wall 4 in such manner that its smaller end projects through a hole in the said wall and has the telephonic receiver 3 connected thereto outside the said wall. The said concave reflector 1 is arranged in such angular relationship to the conduit 2 and to the flat reflector 4, that is to say with its principal focal axis $x-x$ so inclined to such flat reflector that sound projected from the conduit 2 will be reflected as a beam from the parabolic surface of the concave reflector 1 on to the adjacent surface of the flat reflector 4 from whence it will, to a large extent, be radiated outwardly through the outlet orifice A of the structure.

A structure such as described can, as shown, advantageously be housed within a rectangular casing or cabinet 8 in such manner that its open side is parallel with and presented to a perforated front wall 8^a of the casing or cabinet, thus causing the flat reflector 4 to assume a substantially diagonal position across the casing or cabinet, thereby affording accommodation for the telephonic receiver 3 between the flat reflector 4 and the wall of the cabinet, the top and bottom of the cabinet conveniently forming the upper and lower boundary walls 6 and 7 of the trough or scoop shaped structure. One end of the cabinet 8 is provided with a hinged door 9 to admit of ready access to the telephonic receiver 3 for adjustment thereof or for other purpose. Strips 6^a and 7^a of non-resonant material, such for instance as felt, may advantageously be arranged between the edges of the reflectors 1 and 4 and rear wall 5 and top and bottom walls 6 and 7.

Various modifications of this example can be evolved.

For instance, as shown in Fig. 4, the axis $x-x$ of the concave reflector 1 may be inclined to the axis of the sound conduit 2 and to the flat rear wall 5 and also to the inclined flat reflector 4, so that the sound waves reflected from the said concave reflector will be directed wholly or partly on to the rear wall 5 which, acting in this case as a reflector, will cause them to be reflected through the outlet orifice of the structure, the flat reflector 4 also acting to some extent to assist in the outward diffusion of the said waves.

Fig. 5 shows a similar arrangement to Fig. 4 but in which the inclined flat reflector 4 is arranged at a greater angle to the axis $x-x$ of the concave reflector 1 than in the arrangement shown in Fig. 4, (practically at right angles to the said axis,) so that the major portion of the sound waves reflected from the concave reflector 1 impinge upon the rear flat reflector 5 and are thence, to a large extent, reflected on to the inclined flat reflector 4 whence they pass through the outlet orifice of the structure.

Fig. 6 shows an arrangement in which a single flat inclined reflector 4 is combined with the concave reflector 1 and sound conduit 2, the axis $x-x$ of the concave reflector being inclined to the axis of the conduit and also to the flat inclined reflector, so that all sound waves reflected from the concave reflector will impinge against the flat reflector and be reflected therefrom as a diffused beam of sound waves through the outlet orifice 75 of the structure.

When the principal focal axis $x-x$ of the concave reflector 1 is inclined to the axis of the sound conduit 2, as in Figs. 4, 5 and 6, the actual sound emission portion of the conduit may as shown in Fig. 7 at 2^a, be displaced sideways to coincide with the said axis of the reflector.

The concave reflecting surface 2 instead of being of parabolic shape in horizontal section, may be of other conic section.

Although the concave reflector 1 in each of the examples hereinbefore described has been assumed to be straight in cross section in all planes parallel to one edge 1^a thereof (Figs. 90 2 and 3), it need not always be so, and in some cases it may be a concave surface corresponding to that swept through by a curved line rotated about an axis of revolution. The curved line may be that of a 95 parabola or any other suitable curve.

Fig. 8 shows an arrangement of this kind in which the concave reflector 1 has a reflecting surface corresponding to the surface of revolution formed by revolving a 100 curved line of parabolic shape about its principal axis.

An auxiliary reflecting or deflecting surface or device may as indicated at 1^b in Fig. 7, be fitted within the amplifier and radiator.

Instead of using the upper and lower sides of a cabinet to form the upper and lower boundary walls 6 and 7 of the scoop-like structure, as in the example shown in Figs. 1, 2 and 3, top and bottom walls 6^a and 7^a may be combined with the concave and flat reflectors, to form an independent acoustic amplifier and radiator complete in itself, as shown for example in Figs. 8 and 9, and adapted, if desired, to be mounted within an independent cabinet with its outlet orifice A arranged opposite the front of the cabinet which may be of a perforated or openwork character as shown in Figs. 1 120 and 2.

When a cabinet is used, a layer 10 (Fig. 3) of sheet material, for instance textile fabric like silk for example, may be arranged between the said outlet orifice A and the open-work front of the cabinet. When the acoustic amplifier and radiator is enclosed within a cabinet, the space between it and the cabinet, except that containing the telephonic receiver 3, may be filled with non-sonorous ma- 130

terial, as for instance cotton wool, or other fibrous material, to reduce resonance.

In some cases the construction may be such that the smaller end portion of the 5 conduit 2 extends through one of the horizontal walls 6 or 7 of the scoop-like structure, for example through the upper wall 6 and carries the telephonic receiver 3 outside such wall, as shown for example in Fig. 10.

10 What we claim is:—

1. An acoustic amplifier and radiator comprising a concave reflector, a sound conduit having its outlet end opposite said concave reflector and a flat reflector inclined to the 15 axis of said concave reflector and to a sound outlet orifice between them and facing the reflecting surface of said concave reflector.

2. An acoustic amplifier and radiator comprising a concave reflector, a sound conduit 20 having its outlet end disposed opposite said concave reflector with its axis coincident with the axis of said concave reflector and a flat reflector inclined to the axes of the concave reflector and sound conduit and fac- 25 ing the reflecting surface of said concave reflector.

3. An acoustic amplifier and radiator comprising a concave reflector, a sound conduit 30 having its outlet end opposite said concave reflector, a flat reflector, a sound outlet orifice arranged between said reflectors, said flat reflector being inclined to the axis of said concave reflector and to said sound outlet orifice and facing the reflecting surface 35 of said concave reflector and a telephonic receiver connected to the inlet end of said conduit.

4. An acoustic amplifier and radiator comprising a concave reflector, a sound conduit 40 having its outlet end opposite said concave reflector, a flat reflector, and a sound outlet orifice arranged between said reflectors, said flat reflector being inclined to the axis of said concave reflector and to said sound outlet orifice and facing the reflecting surface 45 of said concave reflector and said conduit extending through said flat reflector.

5. An acoustic amplifier and radiator comprising a concave reflector, a flat reflector 50 inclined to the axis of said concave reflector and facing the reflecting surface of said concave reflector, walls formed with said concave and flat reflectors, a scoop shaped structure having a sound outlet orifice at one side, said flat reflector being inclined to the plane of said orifice, and a sound developing conduit extending through said structure and having its outlet orifice disposed 55 opposite said concave reflector.

6. An acoustic amplifier and radiator comprising a concave reflector, a flat reflector 60 inclined to the axis of said concave reflector and facing the reflecting surface of said concave reflector, walls formed with said concave and flat reflectors, a scoop shaped struc- 65

ture having a sound outlet orifice at one side, said flat reflector being inclined to the plane of said orifice, a sound developing conduit extending through the wall of said structure and having its outlet orifice disposed opposite said concave reflector, and a telephonic receiver connected to the inlet end of said conduit and located outside said structure. 70

7. An acoustic amplifier and radiator comprising a concave reflector, a flat reflector 75 inclined to the axis of said concave reflector and facing the reflecting surface of said concave reflector, flat walls formed with said concave and flat reflectors, a scoop shaped structure having a rectangularly shaped sound outlet orifice at one side, said flat reflector being inclined to the plane of said orifice, and a sound developing conduit extending through said flat reflector and having its outlet end disposed opposite said concave reflector. 80

8. An acoustic amplifier and radiator comprising a concave reflector, a flat reflector 85 inclined to the axis of said concave reflector and facing the reflecting surface of said concave reflector, flat walls formed with said concave and flat reflectors, a scoop shaped structure having a rectangularly shaped sound outlet orifice at one side, said flat reflector being inclined to the plane of said 90 orifice, a sound developing conduit extending through said flat reflector and having its outlet end disposed opposite said concave reflector and a telephonic receiver connected to the inlet end of said conduit and located 95 behind said flat reflector. 100

9. An acoustic amplifier and radiator comprising a concave reflector, a flat reflector 105 inclined to the axis of said concave reflector and facing the reflecting surface of said concave reflector, a rear wall connecting the rear ends of said concave and flat reflectors, the front ends of said reflectors being spaced apart to form a sound outlet orifice between them, and a sound conduit having its outlet end disposed opposite said concave reflector. 110

10. An acoustic amplifier and radiator comprising a concave reflector, a flat reflector 115 inclined to the axis of said concave reflector and facing the reflecting surface of said concave reflector, a rear wall connecting the rear ends of said concave and flat reflectors, the front end of said reflectors being spaced apart to form a sound outlet orifice between them, walls forming with the said concave and flat reflectors and rear wall, a scoop shaped structure having a sound outlet orifice at one side thereof and a sound 120 conduit extending through the wall of said structure and having its outlet end disposed opposite said concave reflector. 125

11. An acoustic amplifier and radiator comprising a concave reflector, a flat reflector 130 inclined to the axis of said concave

- reflector and facing the reflecting surface of said concave reflector, a rear wall connecting the rear ends of said concave and flat reflectors, the front ends of said reflectors being spaced apart to form a sound outlet orifice between them, walls forming with the said concave and flat reflectors and rear wall, a scoop shaped structure having a sound outlet orifice at one side thereof, a sound conduit extending through the wall of said structure and having its outlet end disposed opposite said concave reflector and a telephonic receiver connected to the inlet end of said conduit and located outside said structure.
12. An acoustic amplifier and radiator comprising a concave reflector, a flat reflector inclined to the axis of said concave reflector and facing the reflecting surface of said concave reflector, and a straight sound conduit extending through said flat reflector and having its outlet end disposed opposite said concave reflector.
13. An acoustic amplifier and radiator comprising a concave reflector, a flat reflector inclined to the axis of said concave reflector and facing the reflecting surface of said concave reflector, said flat reflector having its front end spaced away from the front end of said concave reflector so as to form a sound outlet orifice between them, a rear wall connecting the rear ends of said concave and flat reflectors and a straight sound conduit extending through the flat reflector and having its outlet end disposed opposite said concave reflector.
14. An acoustic amplifier and radiator comprising a concave reflector, a flat reflector inclined to the axis of said concave reflector and facing the reflecting surface of said concave reflector, said flat reflector having its front end spaced away from the front end of said concave reflector so as to form a sound outlet orifice between them, and a straight sound conduit extending through the flat reflector and having its outlet end disposed opposite said concave reflector, the axes of said concave reflector and sound conduit being substantially coincident.
15. An acoustic amplifier and radiator comprising a concave reflector, a flat reflector inclined to the axis of said concave reflector and facing the reflecting surface of said concave reflector, said flat reflector having its front end spaced away from the front end of said concave reflector so as to form a sound outlet orifice between them, a rear wall connecting the rear ends of said concave and flat reflectors and a straight sound conduit extending through the flat reflector and having its outlet end disposed opposite said concave reflector, the axes of said concave reflector and conduit being substantially coincident.
16. An acoustic amplifier and radiator

comprising a concave reflector, a flat reflector inclined to the axis of said concave reflector and facing the reflecting surface of said concave reflector, said flat reflector having its front end spaced away from the front end of said concave reflector so as to form a sound outlet orifice between them, a rear wall connecting said concave and flat reflectors, walls arranged to form with the concave and flat reflectors and rear wall a scoop-like structure, and a straight sound conduit extending through said flat reflector and having its outlet disposed opposite said concave reflector.

17. An acoustic amplifier and radiator comprising a cabinet having a sound exit at its front side, a concave reflector and a flat reflector arranged within said cabinet between the top and bottom thereof with the flat reflector inclined to the axis of said concave reflector and to the front of said cabinet and facing the reflecting surface of said concave reflector, and a sound conduit extending through said flat reflector and having its outlet end disposed opposite said concave reflector.

18. An acoustic amplifier and radiator comprising a cabinet having a sound exit at its front side, a concave reflector and a flat reflector arranged within said cabinet between the top and bottom thereof with the flat reflector inclined to the axis of said concave reflector and to the front of said cabinet and facing the reflecting surface of said concave reflector, non-resonant material between said reflectors and the top and bottom of said cabinet and a sound conduit extending through said flat reflector and having its outlet end disposed opposite said concave reflector.

19. An acoustic amplifier and radiator comprising a cabinet having a sound exit at its front side, a concave reflector a flat reflector and a rear wall connecting the rear ends of said reflectors, said reflectors and rear wall being arranged vertically within said cabinet and between the top and bottom thereof, and with the flat reflector inclined to the axis of said concave reflector and to the front of said cabinet and facing the reflecting surface of said concave reflector, and a sound conduit extending through said flat reflector and having its outlet end disposed opposite said concave reflector.

20. An acoustic amplifier and radiator comprising a cabinet having a sound exit at its front side, a concave reflector, a flat reflector and a rear wall connecting the rear ends of said reflectors, said reflectors and rear wall being arranged vertically within said cabinet and between the top and bottom thereof, and with the flat reflector inclined to the axis of said concave reflector and to the front of said cabinet

and facing the reflecting surface of said concave reflector, non-resonant material between said reflectors and rear wall and the top and bottom of said cabinet, and a sound 5 conduit extending through the flat reflector and having its outlet end disposed opposite said concave reflector.

21. An acoustic amplifier and radiator comprising a cabinet having a sound exit 10 at its front side, a concave reflector and a flat reflector arranged within said cabinet between the top and bottom thereof with the flat reflector inclined to the axis of said concave reflector and to the front of said cabinet and facing the reflecting surface of 15 said concave reflector, and a straight sound conduit extending through the flat reflector and having its outlet end disposed opposite said concave reflector, the axes of the 20 concave reflector and sound conduit being substantially coincident.

22. An acoustic amplifier and radiator comprising a cabinet having a sound exit at its front side and a door at one end, a 25 concave reflector and a flat reflector arranged within said cabinet between the top and bottom thereof with the flat reflector inclined to the axis of said concave reflector and to the front of said cabinet and 30 facing the reflecting surface of said concave reflector, a sound conduit extending through said flat reflector and having its outlet end disposed opposite said concave reflector and a telephonic receiver connected to the inlet end of said conduit and located 35 within the spaces between the flat reflector and door.

23. An acoustic amplifier and radiator comprising a cabinet having a sound exit 40 at its front side and a door at one end, a concave reflector, a flat reflector, and a rear wall connecting the rear ends of said concave and flat reflectors, said reflectors and rear wall being arranged within said cabinet between the top and bottom thereof 45 with the flat reflector inclined to the axis

of said concave reflector and to the front of said cabinet and facing the reflecting surface of said concave reflector, a sound conduit extending through said flat reflector and having its outlet end disposed opposite said concave reflector and a telephonic receiver connected to the inlet end of said conduit and located within the space between the flat reflector and door. 50

24. An acoustic amplifier and radiator comprising a cabinet having a sound exit at the front and a door at one end, a concave reflector, a flat reflector, and a rear wall connecting the rear ends of said reflectors, 55 said reflectors and rear wall being arranged vertically within said cabinet between the top and bottom walls thereof with the flat reflector inclined to the axis of said concave reflector and to the front of said cabinet, a straight sound conduit extending through the flat reflector and having its outlet end disposed opposite said concave reflector, the axes of said concave reflector and conduit being substantially coincident, 60 and a telephonic receiver connected to the inlet end of said conduit and located between said flat reflector and door. 65

25. An acoustic amplifier and radiator comprising a cabinet having a sound exit 70 at one side, a concave reflector and a flat reflector arranged within said cabinet between opposite walls thereof with the flat reflector inclined to the axis of the concave reflector and to the sound exit side 75 of said cabinet and facing the reflecting surface of said concave reflector, and a sound conduit extending into the space between said reflectors and having its outlet opposite said concave reflector. 80
